UNITED STATES PATENT OFFICE

96,252

DESIGN FOR A STORE FRONT

Pearl Jackman, Detroit, Mich.

Application May 15, 1935, Serial No. 56,839

Term of patent 14 years

To all whom it may concern:

Be it known that I, Pearl Jackman, a citizen of the United States, residing at Detroit, in the county of Wayne and State of Michigan, have invented a new, original, and ornamental Design for a Store Front, of which the following is a specification, reference being made to the accompanying drawing, forming part thereof.

I claim:

The ornamental design for a store front as shown.

PEARL JACKMAN.
